DIRECTIONAL OBSTACLE DETECTING CANE FOR THE BLIND

William A. Ruthven, 3 Fanok Road, Morristown, N.J.
Filed Apr. 22, 1963, Ser. No. 274,457
10 Claims. (Cl. 340—258)

The invention relates in general to devices intended to protect blind persons when traveling on foot by aiding them in the detection of walking hazards in their path of movement, and has particularly reference to canes such as are commonly used for manual exploration of the way.

When out walking, a blind person usually confines his course to well traveled paths or sidewalks extending in his chosen direction of travel, but may cross streets bordered by curbs. The walking hazards likely to be encountered by a blind pedestrian may be divided into two general classes, viz.: (1) depressions in the path level, such as the drop from a curb to street level, descending steps, or a hole or ditch; and (2) obstacles that rise above the path level, such as the bottom one of ascending steps, a stone, brick or piece of lumber lying in the path, a fence, tree or bush close to one side of the path, the curb at the far side of a street being crossed, or the feet of another person standing or walking in front of him.

The canes customarily used by blind persons prior to my present invention do not afford the protection to be desired. The mode of use usually consists in tapping the path at a short distance directly in front of the user's feet and occasionally to right and left of the center of the course. Supposing, for example, that the user of the cane comes to a depression, class (1), such as the curb at the near side of a cross street. The tip, or foot, of the cane will slide over the edge of the curb and jump to the street surface at a point probably a foot beyond the curb. In that distance the duration of reaction time may be so great that the user will trip over the edge of the curb and fall or sprain his ankle. The same will be true in an instance of a class (2) obstacle, such as the bottom step of a stairway. The cane will collide with the obstacle abruptly and stop. The user, having had no time interval of warning, may fall forward onto the steps and bark his shins, at least.

It should now be apparent that the principal disadvantage of the prior art cane relied upon by blind persons is its failure to precede collision with a walking hazard by a warning signal of sufficient duration to permit the user to react safely to the warning.

It, therefore, is the primary object of the present invention to provide the blind with an improved cane in the construction of which I have incorporated means which will communicate to the user a tactile and audible signal of sufficient duration preceding obstructive contact with a walking hazard to enable him to halt his forward progress in time to avoid bodily injury.

To be more explicit, my improved cane is equipped at or near its foot end with walking hazard exploratory means that project respectively straight ahead and laterally to right and left for contact with obstacles in the path of movement of the user. Each exploratory means is yieldable to a necessary degree from front to rear when in obstacle contact. Impulse transmission means is provided to produce tactile and audible signals in the handle of the cane throughout the time interval that each exploratory means is in contact with an obstacle. In most instances the exploratory means is resilient in order that it may become restored automatically to operative condition after an obstacle has been passed by.

A further object of the invention is to cause the tactile indicator means to afford directional indications, i.e. whether the contacted obstacle is straight ahead or to the

2

right or left of the course. To this end, the cane handle has distinct central, right and left portions carrying separately operable signal means.

Another object is to provide a cane for the blind which is equipped to perform all of the functions just enumerated, but which is simple and compact in construction, neat in appearance, light in weight, and capable of manufacture at low cost.

Still further objects, advantages and features of the invention will become apparent as the following specific description is read in connection with the accompanying drawings, in which:

FIG. 1 is a side elevational view of the cane shown in the normal hand-grasped attitude of use;

15 FIG. 2 is a front elevation thereof;

FIG. 3 is a wiring diagram showing the electrical elements of the device and the circuits therefor;

20 FIG. 4 is a large-scale detail side elevation of the supporting wheel and foot end of the cane body, showing the latter broken away and in vertical section with the electric switch for said wheel in open position;

FIG. 5 is a similar view, showing the switch closed;

FIG. 6 is a slightly enlarged horizontal cross-section on line 6—6 of FIG. 1;

25 FIG. 7 is a fragmentary front elevation of the cane body, showing one of the side-feeler walking hazard exploratory members in laterally extended operative position in solid lines and in collapsed inoperative position in broken lines; and

30 FIG. 8 is a vertical section on line 8—8 of FIG. 7 showing the friction locking joint for the collapsible member.

Referring now in detail to the drawings, wherein like reference characters designate corresponding parts in the several views, FIG. 1 shows the cane in the attitude customarily assumed when hand-grasped by the user in his walking progress along a chosen path. The cane includes an elongated body 10 having a head end 11 and a foot end 12.

40 The head end 11 of body 10 is cross-shaped to provide respective laterally extending right and left handle portions 13 and 14 to support distinct right-hand and left-hand tactile indicator means 13' and 14'. Because of their capability of producing both tactile and audible signals, I have chosen electric vibrators, or "buzzers," as the tactile indicator means for the handle portions of cane body 10. It is to be understood, however, that any equivalent means for this purpose may be substituted within the spirit and scope of my invention.

45 It may be explained at this point that tactile indicator means 13' and 14', respectively, will be energized by means to be described later herein when obstacles are encountered closely adjacent to the right and left sides of the user's course of travel. Consequently, the buzzing sound of either tactile indicator vibrator will warn the user that some obstacle has been contacted. By spreading his cane-grasping hand to span both indicator means 13' and 14', the user can determine just what vibrator has been

50 energized and thus distinguish between obstacles located at the right or left side of his course. For indication of obstacles lying directly in front of the user, I have provided a third tactile indicating vibrator 15 in a central position on handle 13—14.

55 At the foot end 12 of cane body 10, a walking hazard exploratory means 16 especially devised for detection of depressions is installed. (See FIGS. 1, 2, 4 and 5.) This exploratory means 16 includes a ground-bearing and cane-supporting member preferably in the form of a wheel 17 journaled in a yoke 18 affixed to a rocker member 19 mounted on a transverse axle 20 in casing 21 carried by said foot end 12 of cane body 10. Rocker mem-

60 65 70 75 80 85 90 95

ber 19 carries a movable electrical contact 22 connected to one branch 23 or bus-wire of an electric circuit that includes a source of electric current 24 (see wiring diagram in FIG. 3), a manual switch 25, and the energizing coil of tactile indicator vibrator 15. The opposite branch 26 of the same circuit is connected to a stationary contact 27 operatively associated with movable contact 22 to form a normally open switch 28. Wheel yoke 18 is affixed to rocker member 19 in a position eccentric to axle 20 such that movable contact 22 will be spaced directly below stationary contact 26 when wheel 17 is rolling on level ground and supporting the weight of the cane. This is the normally open condition of switch 28.

An upwardly inclined skid 29 projects rearward from yoke 18 in rigid relation to the latter in a position to slide over the edge of a depression, such as a street curb, when wheel 17 rolls off and drops, due to failure of ground support, into a position in which movable contact 22 rises against stationary contact 25 of switch 28 to close the circuit of central vibrator 15 and give warning of a depression directly ahead of the user's feet as he walks along.

A supplementary walking hazard exploratory means 30 for detection of obstacles that rise above the ground level directly ahead of the user's feet, is illustrated in FIGS. 1, 2 and 6. This exploratory means 30 includes a forwardly bowed feeler member 31 of resilient strip metal which is arranged to extend crosswise in front of the foot 12 of cane body 10 and has its base end pivotally attached at 32 for oscillation on a vertical axis to the frame of a Micro-switch 33 supported rigidly by casing 21. The base of feeler member 31 is electrically connected to the stationary contact 34 of switch 33 (FIG. 3) and is biased by spring means (not shown) into spaced open-contact relation to movable contact 35 of said switch. Feeler member 31 is in a position to collide with any upstanding obstacle and cause instantaneous closing of the electrical contacts of switch 33. The shape of feeler member 31 is such that it will yield rearwardly throughout a considerable horizontal distance and time interval following initial contact with an obstacle. This time interval should be sufficient to allow for safe reaction by the user of the cane. Referring to the wiring diagram (FIG. 3), it will be observed that switch 33 is connected in parallel with switch 28.

For detection of obstacles located above ground level on either side of the path of movement of the user's feet, I have provided distinct right-hand and left-hand walking hazard exploratory means at two levels, i.e. just above the foot 12 of cane body 10 and substantially midway of said body. Identical exploratory means 36R and 36L respectively, are positioned on the right and left sides of cane body 10 at the lower level, and 37R and 37L, respectively, on the right and left sides at the higher level. Each of these exploratory means 36R, 36L, 37R and 37L includes a limber feeler member 38 of articulated construction, having a main arm 39 pivoted on a substantially horizontal fore-and-aft axis 39a to a substantially vertical base arm 40, which latter in turn is pivotally supported on a lateral horizontal axis by a Micro-switch 41 carried by cane body 10. Base arm 40 is electrically connected to the stationary contact 42 of the Micro-switch 41 (FIG. 3) and is biased by spring means (not shown) from contact with the movable contact 43 thereof. In other words, the general arrangement of arm 40 and the principal electrical elements of this Micro-switch 41 is the same as the arrangement of the corresponding parts of the walking hazard exploratory means 30 disclosed in FIGS. 1, 2 and 6. In this instance, however, main arm 39 is adapted to be swung on its pivotal axis 39a between operative position wherein it extends laterally from cane body 10 and inoperative position hanging close to said body, as when the cane is not in use and possibly stored in a hall closet. Some convenient means, such as a friction joint or clamping screw 39b (FIG. 8), should be provided at

the pivotal connection 39a of main arm 39 and base arm 40 to secure the said main arm rigidly in either of its adjusted positions.

The switches for the respective walking hazard exploratory means 36R, 36L, 37R and 37L are designated 41LR, 41LL, 42UR and 42UL (FIG. 3).

Right-hand tactile indicator vibrator 13' has one electrical terminal connected to the upper end of bus-wire 23 by conductor 44 and its other terminal connected by conductor 45 through switch 41LR to the lower end of said bus wire and by conductor 46 through switch 41UR to the said lower end of said bus wire, i.e. in bridging relation to source of electric current 24. On the opposite side of cane body 10, left-hand tactile indicator vibrator 14' has one electrical terminal connected to the upper end of bus-wire 23 by conductor 47 and its other terminal connected by conductor 48 through switch 41LL to the lower end of said bus wire and by conductor 49 through switch 41UL to the said lower end of said bus wire; i.e. in bridging relation to source 24.

To complete the useful features of the cane, an electric blinder light 50, preferably red, is connected by a circuit 51 containing a manual switch 52 to bus-wire 23 in bridging relation to source 24.

Operation

Before starting out for a walk with the protective aid of the improved cane, the user turns switch 25 into "ON" position and swings main arms 39 of the respective walking hazard exploratory means 36R, 36L, 37R and 37L into horizontally extending operative positions. Then, he grasps handle portions 13 and 14 with one hand in such a manner that his palm covers all three tactile indicator vibrators 13', 14' and 15.

Assuming that he arrives at the curb on the near side of a street, wheel 17 will jump the curb and skid 29 will slide over the edge of the latter until wheel 17 has landed on the street surface and is ready to roll forward again. While this is happening, the wheel assembly 17-18-19 will have rocked on axle 20 until switch 28 has closed and caused energization of tactile indicator vibrator 15. Through the sense of touch in the center of the palm of his hand, the cane's user will become aware of the curb contact, and the signal will persist for one or more seconds of time, which should be sufficient for him to come to a stop before he can stumble over the curb and become injured. When his feet reach the curb, he can identify it with his feet and then proceed across the street. At this juncture, he can warn the drivers of vehicles and other pedestrians that a blind person is crossing the street by switching on red blinder light 50.

Assuming further that the user of the cane reaches the opposite curb safely, the feeler member 31 of supplementary walking hazard exploratory means 30 will contact the upstanding curb and be deflected rearwardly to close switch 33 and again energize tactile indicator vibrator 15. All the while feeler member 31 is yielding to curb contact, the tactile indicator signal will be warning of the obstacle encountered in time for safe reaction.

Should the cane's user approach an upstanding obstacle closely adjacent to the path of movement of his feet at either side of said path, such as a wall, tree or rock, he will be warned by transmission of an electrical impulse from one of the walking hazard exploratory means 36R, 36L (for low obstacles) or 37R, 37L (for tall obstacles). For instance, if an obstacle at the right of the path is encountered, either exploratory means 36R, or both exploratory means 36R and 37R, (depending upon the height of the obstacle), will yield and close switches 41LR and/or 41UR, thereby energizing right-hand tactile indicator vibrator 13' and warning the user of an obstacle upstanding on his right. Similarly, collision of walking hazard exploratory means 36L and/or 37L with an upstanding obstacle on his left will yield

and close switch 41LL and/or 41UL to thereby cause energization of left-hand tactile indicator vibrator 14'.

It should now be apparent that encounter with any obstacle with which my cane is able to cope will result in an audible buzzing signal regardless of its direction from the user of the cane. At the same time, a directional indication will be conveyed by the sense of touch either at the center of his palm or at right or left, as the case may be.

While the invention has been illustrated and described with respect to a few particular embodiments thereof, it will be understood that it is intended to cover all changes and modifications of the embodiments shown which do not constitute departures from the spirit of the invention and scope of the appended claims.

I claim:

1. A directional obstacle detecting cane for blind persons comprising:
  - an elongated cane body having head and foot ends;
  - a handle section provided on the head end of the cane body;
  - a tactile indicator in the form of an electric vibrator mounted on said handle section;
  - an electric circuit in which said vibrator is connected; normally open switch means connected in said electric circuit and including stationary and movable contacts; and
  - walking hazard exploratory means supported by said cane body and including a rearwardly yieldable obstacle contacting member constructed and arranged in relation to said switch means in a manner to close said electric circuit when caused to yield by obstacle contact and thereby energize the vibrator.

2. The invention defined in claim 1, wherein the walking hazard exploratory means is located in close proximity to the foot end of the cane body.

3. The invention defined in claim 2, wherein the walking hazard exploratory means projects forward from the foot end of the cane body and is rearwardly resiliently yieldable.

4. The invention defined in claim 1, wherein the walking hazard exploratory means includes at least two substantially identical tenuous members projecting laterally to the right and to the left respectively from the cane body; wherein the tactile indicator handle means includes two distinct independently operable sections located respectively at the right and left side of the cane body; wherein there are added two distinct tactile indicator vibrators which are mounted on the respective handle sections; wherein distinct normally open electric switches are provided for the respective walking hazard exploratory members; and wherein a separate electric circuit connects each walking hazard exploratory member with the corresponding tactile indicator vibrator in such a manner that rearward deflection of either one of said exploratory members will cause energization of the tactile indicator vibrator at the corresponding side of the cane body, whereby the cane user can determine the direction of the obstacle.

5. The invention defined in claim 4, wherein the walking hazard exploratory means includes one member lo-

cated directly in front of the cane body; wherein the tactile indicator handle means includes a third central section located intermediate of the right and left sections; and wherein the tactile impulse transmitting means includes means separately connecting said front exploratory member to the central tactile indicator handle section.

5 6. The invention defined in claim 5, wherein electric vibrator means is located at each section of the tactile handle means; wherein a normally open electric switch is connected to each walking hazard exploratory member in such a manner that the switch will be closed whenever said exploratory member is deflected by collision with an obstacle; and wherein the tactile impulse transmitting means comprises electrical circuits connecting the respective exploratory members to the corresponding tactile handle sections.

10 7. The invention defined in claim 4, wherein each laterally projecting tenuous member of the walking hazard exploratory means includes a substantially vertical rigid base arm which is terminally pivoted on a horizontal lateral axis to the cane body and a limber feeler member of articulated construction which is pivoted to the free end of said base arm on a substantially horizontal fore-and-aft axis in a manner to permit collapse of said feeler member into inoperative position close to said cane body in substantial parallelism with respect thereto.

15 8. The invention defined in claim 7, wherein friction means is added at the pivot joint between the base arm and feeler member to secure the latter yieldably in adjusted position.

9. The invention defined in claim 1, wherein the walking hazard exploratory means includes:

20 a rocker arm pivotally connected to the foot of the cane body on a transverse horizontal axis; a ground-bearing member located beneath said foot of the cane body in attachment to said rocker arm eccentrically rearward of the pivotal axis thereof and being arranged for ground-bearing contact forwardly with respect to said pivotal axis in such a manner that the contacts of the electric switch means will be open when said ground-bearing member is supporting the cane upon the ground and will become closed whenever said ground-bearing member drops into a depression.

25 10. The invention defined in claim 9, to which is added an elongated upwardly inclined skid projecting rigidly rearward from the ground-bearing member.
